[57] CLAIM

The ornamental design for a goggle, as shown and described.

DESCRIPTION

FIG. 1 is a perspective view of a goggle showing my new design of the present invention;

FIG. 2 is a front elevational view thereof;

FIG. 3 is a side elevational view thereof as viewed from the right side of FIG. 2, the opposite side being a mirror image thereof;

FIG. 4 is a top plan view thereof;

FIG. 5 is a bottom view thereof; and,

FIG. 6 is a rear elevational view thereof.
